UNITED STATES PATENT OFFICE.

BENJAMIN EDWARD MEACHAM, OF LORAIN, OHIO, ASSIGNOR TO AMERICAN STOVE COMPANY, OF ST. LOUIS, MISSOURI, A CORPORATION OF NEW JERSEY.

LEG ATTACHMENT FOR STOVES.

Application filed September 29, 1926. Serial No. 138,425.

This invention relates to improvements in leg attachments for stoves and the general idea thereof is to so construct the leg that a substantial attachment is made and one that is easily applied to the base of the stove.

One object of the present invention is to construct its parts so that it is quickly and readily connected with the base of the stove.

A further object of the invention is to make the construction with substantially a three point bearing having holding means in such a position that the leg is firmly and substantially held without a tendency to become loose and wobbly if the stove is moved about on the floor.

Another object of the invention is to provide the leg with points so arranged and long enough to prevent the enameled surfaces on the leg from being chipped when attaching it to the base of the stove, which is a very serious fault with stoves having enameled surfaces as heretofore constructed.

Another object of the present invention is to so construct the leg that the holding means or bolts will be concealed after the leg is attached to the base.

It is usual to ship the legs separately from the stove, and a further object of the invention is to so construct the parts that any one can readily and quickly attach the leg to the base of the stove.

Further objects of the invention will appear from the following description.

In the accompanying drawings:

35. Figure 1 is a detached perspective view of my improved leg attached to part of the base of the stove.

Figure 2 is a horizontal sectional view on the line 2—2 looking in the direction indicated by arrow.

Figure 3 is a vertical sectional view on the line 3—3 of Figure 2.

Figure 4 is a detached perspective view of the upper end of the leg and part of the base, the said parts being shown in detached relation.

Figure 5 is a side elevation of the upper end of the leg looking at the same from its inner side.

50. This invention is intended more particularly to be applied to the leg and base of a

gas stove, in which the leg is made relatively long. The present invention also pertains to a stove in which the leg is enameled, and in some instances also the base to which 55 the leg is attached.

Referring now to the drawings, 1 is an elongated leg, its upper end being shown attached to a base 2 of a gas or other similar stove. The base in this instance is made 60 from L-shaped material, the same consisting of a vertical flange 3 and a horizontal flange 4 extending inward from the said vertical flange. This base is formed from a single piece, and by cutting it out substantially as 65 shown at 5, the said vertical wall 3 is bent at 6 until its parts are at right angles to each other. A base of this construction is not new.

The upper end of the improved leg, which 70 is preferably made from cast material and has its surface wholly enameled, is constructed substantially as follows:

Referring now particularly to Figure 4, the upper end of the leg has an inwardly 75 extending horizontal flange 7 around its upper end, the said flange in plan view being a right angle. Formed integral with this horizontal flange 7 and extending upward from its inner edge is a relatively much wider 80 vertical flange 8. Attention is directed to the formation of this horizontal flange 7 and to the upper edge 9 of the vertical flange 8. The construction above referred to consists in forming on the horizontal flange points 85 10 located at the outer ends of the said flange 7 and a point 11 which joins the inner ends of the flange 7. These points 10 and 11 extend above the flange 7 and are therefore in a horizontal plane above the plane of the flange 7 itself. Projecting upward from the outer ends of the vertical flange 9 are vertical projections 12, and at the inner ends of the flange 9 a vertical projection 13. The points 10 and 11 form bearings for the lower 90 edge of the vertical portion 3 of the L-shaped base 2, and the projections 12 and 13 form corresponding bearings for the horizontal portion 4 of the base 2. Preferably the projections 12 and 13 are higher as compared with the projections 10 and 11, and the object of this is to prevent chipping the 95 100

enamel on the upper end of the leg when applying it to the base 2. Thus it will be seen that when the base is applied to the upper end of the vertical portion 8 of the leg, that spaces 14 are formed between the upper portion of the leg and the lower edge of the base 3. Also by forming the flange 7 with the projections 10 and 11, a wider space is formed between the flange and the lower edge of the said base. This construction in practice serves to prevent the chipping of the upper end of the leg in places where it would show when the leg is being connected with the base 2.

Attention now is directed to the means for attaching the said leg to the base 2 whereby the attachment is readily made by one not skilled in the art, and is so made as to make it rigid and to prevent the leg from becoming wobbly when moving the stove around on the floor. This means of attachment comprises the horizontal inwardly extending flanges 15 which are located at opposite sides of the point 13 and located substantially midway between the upper ends of the upper points 12 and 13 and the lower edge 16 of the leg. Both of these flanges have inwardly extending U-shaped passages 17 which receive the holding bolts 18. These bolts 18 pass through suitable openings 19 and are attached to the horizontal portion 4 of the base by nuts 20 which are tightly screwed against the under side of the horizontal flange 4 of the base. This is done when the leg leaves the factory and is packed separately and shipped with the stove. Consequently the base has thus permanently attached to it the bolts and the bolts are prevented from rotating. In applying the leg it is only necessary that the bolts be inserted in the U-shaped openings 17 and the securing nuts 21 applied thereto and clamped rigidly against the underside of the flanges 15.

By locating these parts as described when the nuts 21 are in position, it makes a rigid attachment of the said leg to the base, serving to hold it firmly even against wobbling when the stove is moved along on the floor. In thus applying the leg to the base it will be understood that the bolt is prevented from turning by the nuts 20 when the clamping nuts 21 are applied to the lower ends thereof.

I wish it understood that slight changes may be made in the construction here shown and described without departing from the spirit and scope of the invention, so long as the changes come within a fair interpretation of the appended claims.

Having thus described my invention, what I desire to claim and secure by Letters Patent is:

1. A stove leg attachment, the upper end of the leg having a vertical extending flange

with projections extending upwardly from the upper end thereof, horizontal flanges extending from the inner wall of said vertical flange, said horizontal flanges having bolt openings, and a base portion extending over the horizontal flanges and resting on the said projections, and bolts passing through the overlying portion of the base and the openings in the horizontal flanges thus serving to connect the parts together. 75

2. A stove leg attachment having at its upper end a vertical extending flange, the upper edge of the flange provided with central and end projections, the vertical flange having inwardly extending horizontal flanges with bolt openings, and L-shaped base portion having the vertical portion thereof at the outer side of the vertical flange and the horizontal portion resting on the said three points, and bolts passing through 85 the horizontal part of the base and the openings in the horizontal flanges for connecting the parts together.

3. A stove leg attachment comprising a leg having at its upper end a vertical extending flange offset from the rest of the leg, the vertical flange having at its inner side inwardly extending horizontal flanges with bolt openings, combined with an L-shaped base portion the vertical legs of which are 90 of less height than the height of the vertical flange whereby chipping of the enamel on the leg portion is prevented, and bolts passing through the horizontal portion of the base and through the horizontal flanges for 95 uniting the parts together. 100

4. A stove leg attachment comprising a leg portion having at its upper end a vertical flange, the said flange having at its inner side horizontal flanges with bolt openings, and an L-shaped base portion applied to the vertical flange, the horizontal portion extending over the said horizontal flanges, bolts connecting the parts together, the upper portion of the leg lying below the lower edge of the 110 vertical portion of the L-shaped flange being depressed for the purpose of preventing chipping of the enamel on the said leg when applying it to the base portion. 105

5. A stove leg attachment having at its 115 upper end a vertical extending offset flange, said offset forming a shoulder, upwardly extending projections forming a part of said flange, a base portion having a part thereof at the outer side of the vertical flange and a 120 second part resting on the flange projections, whereby the end of the base portion at the outer side of the vertical flange is supported above and in separated relation in respect to said shoulder, and means to fasten the 125 base to the leg.

6. A stove construction comprising, a leg having at its upper end an upwardly extending projection, an L-shaped stove base piece having its outer vertical portion out- 130

side of said leg projection and its horizontal portion resting on the upper extremity of said leg projection and supported thereby, the inner wall of the projection extending inwardly and provided with bolt openings, said horizontal portion of the stove base piece overlapping said openings, and bolts passing through the horizontal stove base piece and through said opening, thus uniting the parts together.

In testimony whereof I hereunto affix my signature.

BENJAMIN EDWARD MEACHAM.
